UNITED STATES PATENT OFFICE.

ISAAC H. COX, OF BRIDGETON, NEW JERSEY.

CAN-SOLDERING MACHINE.

SPECIFICATION forming part of Letters Patent No. 278,100, dated May 22, 1883.

Application filed February 28, 1883. (Model.)

To all whom it may concern:

Be it known that I, ISAAC H. COX, of Bridgeton, in the county of Cumberland, and in the State of New Jersey, have invented certain new and useful Improvements in Can-Soldering Machines; and I do hereby declare that the following is a full, clear, and exact description thereof, reference being had to the accompanying drawings, making a part of this specification, in which—

Figure 1 is a perspective view of my machine as arranged for use. Fig. 2 is a like view of the same when in use. Fig. 3 is a vertical central view upon a line passing lengthwise of the frame, and Fig. 4 is a vertical central cross-section.

Letters of like name and kind refer to like parts in each of the figures.

The design of my invention is to enable the caps to be simultaneously soldered upon a number of cans; and to this end it consists in the means employed for rotating the soldering-irons, substantially as and for the purpose hereinafter shown and described.

It consists, further, in the means employed for moving the soldering-irons toward or from the cans, substantially as and for the purpose hereinafter specified.

It consists, further, in the means employed for heating the soldering-irons, substantially as and for the purpose hereinafter shown.

It consists, further, in the means employed for cleaning and retinning the soldering-irons, substantially as and for the purpose hereinafter shown and described.

It consists, finally, in the machine as a whole, its parts being constructed and combined to operate in the manner and for the purpose substantially as hereinafter specified.

In the annexed drawings, A represents a rectangular frame having a horizontal bottom, a, and an open upper side, and supported at a suitable height by means of legs B, which are preferably placed near or at the corners of said frame, and have their lower ends secured in place upon a floor.

Fitted loosely within the frame A is a plate, C, which corresponds in horizontal dimensions to the like features of the interior of the same, and at each end is provided with an arm, c, that extends outward through a vertical slot, a', which is formed in the contiguous end of

said frame and terminates in a round boss, c'. Said boss is engaged by the concave upper end of a bar, D, which at its lower end is jointed to one end of a lever, E, that is pivoted to or upon the end of said frame, and has its outer end connected by means of a pivoted bar, F, to or with the corresponding end of a similar lever, E, located at the opposite end of the machine, the arrangement being such as to permit said levers to be simultaneously operated by said rod, so as to move said plate C vertically within said frame A.

Journaled in two parallel lines within the plate C, and extending downward through the bottom a of the frame A, are a number of soldering-irons, which consist each of a cylinder, G, having at its upper end a journal, g, and above the same a toothed pinion, g', said cylinder being below said plate and said pinion above the same.

Between the rows of pinions g' is a rack-bar, H, which has its side edges, h, toothed to engage with said pinions, and is provided upon its face with a central longitudinal line of teeth, h', that are engaged by a toothed segment, I, which is provided with a radial handle, i. Said segment is pivoted between two ears, c², that are secured to the plate C and extend upward therefrom through two longitudinal slots, h², which are provided in said rack-bar. As thus arranged, the oscillation of said toothed segment upon its pivotal bearing will cause said toothed rack-bar to be moved to and fro longitudinally, and said pinions, with the soldering-irons G, to be partially or entirely rotated in opposite directions.

The lower ends of the soldering-irons G have such shape as to enable each to fit over the cap k of a cam, K, and, being heated and raised sufficiently a number of cans corresponding to the number of said soldering-irons are supplied with caps and solder and arranged within a suitable box, L, and placed beneath the frame A in such position as to bring each can directly beneath one of said soldering-irons, after which the latter are lowered until they rest upon said cans, and are then rotated until said solder has become melted.

In order that variation in the height of the cans K may not prevent the perfect operation of the soldering-irons G, the journal g of each of the latter has such length as to permit of

a considerable amount of vertical motion within the plate C, by which construction each soldering-iron is free to move in such direction within the necessary limits without affecting 5 the movements or operation of the other soldering-irons.

Each cap k is held in place before the soldering-irons G are brought into operation, and afterward, while the solder is cooling, by means 10 of a rod, M, which passes loosely through an axial opening, g², in each of said soldering-irons, and at its upper end is provided with a weight, m. Said rod has such length as to cause its lower end to project considerably below 15 the lower end of its soldering-iron when the latter is raised from contact with a can. In use said rods impinge upon said caps before said soldering-irons come into contact therewith, and hold them in place while being operated upon by said soldering-irons, while after the latter are raised from contact with said caps said rods maintain their contact and hold said caps in place while the solder is cooling.

The box L is preferably kept in lateral position by means of a rail, N, which is secured to or upon the floor and over which said box slides, while its longitudinal position is insured by a stop, O, that projects from either said rail or floor and engages with the end of said box.

30 In order that the soldering-irons G may be easily cleaned and retinned, I provide for each a block, P, which corresponds in size and general shape to the like features of the cans K, and at its upper end has a recess, p, which is exactly the reverse of the shape of the lower end of each soldering-iron. Each block P has its recess p now supplied with acid and solder, and is placed within the box or tray L, and the latter then moved to place beneath said soldering-irons, after which the latter are lowered into contact with said blocks, and then rotated in the same manner as when cans are being capped, the result being the easy and perfect cleaning and retinning of said irons.

45 In order that the soldering-irons G may be heated to and maintained at the necessary temperature, I provide for each pair a burner, Q, which passes through the frame A at a point midway between said soldering-irons, and 50 is adapted to throw horizontally inward a flame. Immediately in front of said burner I place a Λ-shaped deflector, q, upon which the flame impinges and is divided, one-half being directed against each soldering-iron. The amount of combustible material permitted to 55 be consumed by said burner governs the temperature of said soldering-irons and enables each to be kept at the most efficient point.

Having thus fully set forth the nature and 60 merits of my invention, what I claim as new is—

1. A can-soldering machine provided with two or more soldering-irons journaled in a vertically-reciprocating plate, a sliding rack on such plate gearing with pinions on the upper 65 ends of the rotating irons, and means for actuating the rack, substantially as and for the purpose set forth.

2. In combination with the journaled soldering-irons G, provided each with a pinion, g', 70 the rack-bar H, having toothed side edges which mesh with said pinions, and adapted to be reciprocated longitudinally by means of the pivoted toothed segment I, substantially as and for the purpose shown and described. 75

3. In a can-soldering machine, in combination with each pair of rotary and reciprocating soldering-irons, the burner Q, projecting inward through the side of the frame, and the deflector fixed on the bottom plate of the frame, 80 between the soldering-irons, substantially as and for the purpose described.

4. In combination with the plate C, adapted to carry the journaled soldering-irons G, and provided with the arms c and bosses c', the 85 hinged bars D, pivoted levers E, and bar F, substantially as and for the purpose shown.

5. In combination with the soldering-irons G, the cleaning and tinning blocks P, having their upper ends fitting over or upon the lower 90 ends of the former, and contained within the box L, substantially as and for the purpose shown and described.

6. In a can-soldering machine, the combination of the slide provided on both sides with rack-teeth to engage the two rows of pinions on the soldering-irons, the ears attached to the bearing-plate and extending up through slots in the slide, and the actuating mechanism journaled in said ears, all so arranged that the 95 ears act with the slots as guides for the slide, substantially as specified. 100

7. In a soldering-machine, the combination of the following elements, to wit: the series of soldering-irons journaled vertically in a vertically-movable plate, the rack sliding on and supported by the plate, and engaging the pinions attached to the soldering-irons, operating mechanism therefor, the weighted rods for holding the cans in place, and means for holding the cans in position while they are being operated upon, all substantially as and for the purpose set forth. 105

In testimony that I claim the foregoing I have hereunto set my hand this 16th day of 110 February, 1883.

ISAAC H. COX.
